[57] ABSTRACT

A device for creating optical illusions comprising a transparent sheet, a plurality of fresnel screens spaced apart and in a regular array on the sheet, a condensing lens formed by each of the fresnel screens and a reflecting surface juxtaposed with the sheet.

OPTICAL-ILLUSION DEVICE

The present invention relates, in general, to optical-illusion devices and, more particularly, to optical-illusion devices employing light-condensing and light-reflecting means, both moving and stationary.

Heretofore, illusion devices of the above-mentioned type consisted mainly of kaleidoscopes, using a system of angled mirrors and multi-colored, translucent inserts and image-projection devices.

It is, therefore, an object of the invention to provide an optical illusion device for creating a plurality of stationary, up-right images.

Another object of the invention is to provide an optical illusion device for creating a plurality of orbiting, up-right images.

The above-mentioned objects and others, which will become apparent hereinafter, are achieved by forming, on a transparent sheet, a plurality of fresnel screens, preferably comprised of concentric grooves, centered on the geometric center that the particular screen outline defines.

The fresnel screens, which act, in the system of the invention, as condensing lenses, are arranged in an array across the transparent sheet, which is juxtaposed with a reflecting surface, such as a mirror. The array may comprise orthogonal rows of spaced condensing lenses.

According to a more specific feature of the invention, the transparent sheet and mirror are adjacent and closely juxtaposed, and are held in a common frame, which is manually movable or is provided with a motor for rotating the sheet.

A viewer, juxtaposed with the sheet and mirror arrangement, will see his reduced, up-right image formed on each of the screens, after his image has passed through, and been reduced by, the condensing fresnel screens and reflected back from the mirror to the screens. A conventional lens (without the fresnel screen) will merely pass light in either direction and display images at its surface.

If the transparent sheet is rotated, the viewer will see his up-right images orbiting about a central point.

The above and other objects, features and advantages of the invention will become more readily apparent from the following description, reference being made to the accompanying drawing, in which:

FIG. 1 is a perspective view of a device according to the invention;

FIG. 1A is a section taken along line 1A in FIG. 1;

FIGS. 2 and 3 are plan views of FIG. 1 in different positions;

FIG. 4 is a sectional view of another embodiment of the invention;

FIG. 5 is a sectional view of still another embodiment of the invention;

FIG. 6 is a perspective view of a further embodiment of the invention;

FIG. 7 is another perspective view of yet a further embodiment of the invention; and

FIG. 8 is a plan view of yet another embodiment of the invention;

FIGS. 9-12 are sectional views of different embodiments according to the invention.

The embodiment of the optical illusion device 10, shown in the drawing of FIG. 1, has a rectangular, transparent sheet 1, made of a synthetic resin having a series of fresnel screens 2 formed in the surface 1'.

The screens 2 have a rectangular outline and are arranged in vertical and horizontal rows which are spaced apart, leaving clear strips 3 surrounding the screens 2.

As can best be seen in FIG. 1A, the fresnel screens 2, which act as condensing lenses, are formed in the surface 1' of sheet 1 by pressing or stamping with a heated die.

The screens 2 are comprised by concentric circular grooves 2' separated by ridges 2'', the grooves 2' being somewhat wider than the ridges 2'', the grooves 2' and ridges 2'' being concentric with the axis "O" of the screen 2.

The sheet 1 is adjacent a reflecting surface, such as a mirror 4, the sheet 1 and the mirror 4 being held in place by a frame 5

which surrounds them, the frame 5 having a groove 5' into which the sheet 1 is fitted and a further groove 5'' into which the mirror 4 is fitted, the sheet 1 and the mirror 4 being held in a fixed, spaced-apart relationship by the grooves 5' and 5''.

5 In operation, an object, such as the pencil 6, is held in front of the sheet 1. The light reflected from the pencil 6 passed through the clear strips 3 surrounding the screens 2, forming an image 6' on the mirror 4, as can best be seen in FIG. 2, which is reflected back through the clear strips 3, to an observer juxtaposed with the device 10, beyond the pencil 6. The light reflected from pencil 6 also passes through the screens 2, where the light from the pencil 6 is condensed and passes on to the mirror 4 where a reduced image 6'' of the pencil 6 is formed and reflected back through the screens 2, where the reflected light is further condensed, the twice reduced image 6''' appearing on the fresnel screens 2 which, in addition to acting as a condensing lens, provides a surface on which an image can be formed.

10 The images 6''' formed on the screens 2 are upright and remain so when the device 10 is rotated, as seen in FIG. 3, giving an illusion of a multitude of independently rotating images 6''', revolving about a central image 6'.

In FIG. 6, an optical device 11, specifically designed for 15 rotating, comprises a circular transparent sheet 41 having an array of circular condensing fresnel screens 42, formed in the surface 41'.

The sheet 41 is rotatably held by a frame 45, adjacent to a 20 mirror 44, the sheet 41 being driven by a motor 12 and a toothed wheel 13, engageable with teeth 14 provided along the periphery 15 of sheet 41.

25 The sheet 41 is rotatably held by a frame 45, adjacent to a mirror 44, the sheet 41 being driven by a motor 12 and a toothed wheel 13, engageable with teeth 14 provided along the periphery 15 of sheet 41.

30 The sheet 41 is rotatably held by a frame 45, adjacent to a mirror 44, the sheet 41 being driven by a motor 12 and a toothed wheel 13, engageable with teeth 14 provided along the periphery 15 of sheet 41.

35 The sheet 41 is rotatably held by a frame 45, adjacent to a mirror 44, the sheet 41 being driven by a motor 12 and a toothed wheel 13, engageable with teeth 14 provided along the periphery 15 of sheet 41.

The embodiments shown in FIG. 4 and 5 are similar to that of FIG. 1 except for the mirror 24, which is convex in one plane and the mirror 34, which is concave in one plane. If either or these embodiments is rotated as a unit, the images formed will appear to pulsate as the plane of distortion rotates, in addition to the other illusions earlier mentioned.

40 The sheet 41 is rotatably held by a frame 45, adjacent to a mirror 44, the sheet 41 being driven by a motor 12 and a toothed wheel 13, engageable with teeth 14 provided along the periphery 15 of sheet 41.

The sheet 41 is rotatably held by a frame 45, adjacent to a 45 mirror 44, the sheet 41 being driven by a motor 12 and a toothed wheel 13, engageable with teeth 14 provided along the periphery 15 of sheet 41.

50 The sheet 41 is rotatably held by a frame 45, adjacent to a mirror 44, the sheet 41 being driven by a motor 12 and a toothed wheel 13, engageable with teeth 14 provided along the periphery 15 of sheet 41.

55 The sheet 41 is rotatably held by a frame 45, adjacent to a mirror 44, the sheet 41 being driven by a motor 12 and a toothed wheel 13, engageable with teeth 14 provided along the periphery 15 of sheet 41.

60 The sheet 41 is rotatably held by a frame 45, adjacent to a mirror 44, the sheet 41 being driven by a motor 12 and a toothed wheel 13, engageable with teeth 14 provided along the periphery 15 of sheet 41.

65 The sheet 41 is rotatably held by a frame 45, adjacent to a mirror 44, the sheet 41 being driven by a motor 12 and a toothed wheel 13, engageable with teeth 14 provided along the periphery 15 of sheet 41.

The sheet 41 is rotatably held by a frame 45, adjacent to a mirror 44, the sheet 41 being driven by a motor 12 and a toothed wheel 13, engageable with teeth 14 provided along the periphery 15 of sheet 41.

70 The sheet 41 is rotatably held by a frame 45, adjacent to a mirror 44, the sheet 41 being driven by a motor 12 and a toothed wheel 13, engageable with teeth 14 provided along the periphery 15 of sheet 41.

The sheet 41 is rotatably held by a frame 45, adjacent to a mirror 44, the sheet 41 being driven by a motor 12 and a toothed wheel 13, engageable with teeth 14 provided along the periphery 15 of sheet 41.

75 The sheet 41 is rotatably held by a frame 45, adjacent to a mirror 44, the sheet 41 being driven by a motor 12 and a toothed wheel 13, engageable with teeth 14 provided along the periphery 15 of sheet 41.

The sheet 41 is rotatably held by a frame 45, adjacent to a mirror 44, the sheet 41 being driven by a motor 12 and a toothed wheel 13, engageable with teeth 14 provided along the periphery 15 of sheet 41.

80 The sheet 41 is rotatably held by a frame 45, adjacent to a mirror 44, the sheet 41 being driven by a motor 12 and a toothed wheel 13, engageable with teeth 14 provided along the periphery 15 of sheet 41.

85 The sheet 41 is rotatably held by a frame 45, adjacent to a mirror 44, the sheet 41 being driven by a motor 12 and a toothed wheel 13, engageable with teeth 14 provided along the periphery 15 of sheet 41.

90 The sheet 41 is rotatably held by a frame 45, adjacent to a mirror 44, the sheet 41 being driven by a motor 12 and a toothed wheel 13, engageable with teeth 14 provided along the periphery 15 of sheet 41.

95 The sheet 41 is rotatably held by a frame 45, adjacent to a mirror 44, the sheet 41 being driven by a motor 12 and a toothed wheel 13, engageable with teeth 14 provided along the periphery 15 of sheet 41.

I claim:

1. A device for creating optical illusions, comprising a rectangular planar transparent sheet, a plurality of rectangular flat Fresnel screens formed in said sheet, said screens being spaced apart from each other in a rectangular matrix array, the space between said screens defining a lattice of mutually orthogonal clear strips, a rectangular planar continuous

reflecting surface adjacent to and parallel with said sheet, said surface being substantially coextensive with said sheet, and a frame surrounding said sheet and said surface for holding said sheet and said surface in a fixed relationship to each other.
